UNITED STATES PATENT OFFICE.

DENYS WARWICK MORLEY, OF LEICESTER, ENGLAND, ASSIGNOR TO UNITED SHOE MACHINERY CORPORATION, OF PATERSON, NEW JERSEY, A CORPORATION OF NEW JERSEY.

MARKING MACHINE.

Application filed May 15, 1922. Serial No. 561,094.

To all whom it may concern:

Be it known that I, DENYS W. MORLEY, a subject of the King of England, residing at Leicester, Leicestershire, England, have 5 invented certain Improvements in Marking Machines, of which the following description, in connection with the accompanying drawings, is a specification, like reference characters on the drawings indicating like parts in the several figures.

This invention relates to marking machines and is herein shown as embodied in a machine for marking articles by the application of metal leaf.

15 A machine which has been commonly used for marking shoe uppers and the like with identifying numbers or other symbols comprises a type head having a series of type wheels mounted on an oscillating arm which 20 carries the type into contact with the work. Sometimes an additional line of printing is furnished by a so-called stock plate attached to the type head, either in front of, or behind the line of printing furnished by 25 the type wheels. It is an object of this invention to provide a machine of this character in which the marking medium can be applied economically to the impression members from a continuous strip of material, 30 such as embossing leaf. Such a mark is more ornamental than ink and is in considerable demand for embossing the top stays or shoes or the like. This embossing leaf comes in the form of a metallic powder applied uniformly to a backing of filmsy paper. 35 This material is expensive and the strip is easily torn but, if the difficulties encountered in the handling of the delicate material can be overcome, it is preferable to 40 pastes and suspensions of the metallic marking material which, in use, are apt to change in character and consistency.

As one feature of the invention the strip of marking material is fed intermittently in 45 the direction of its length beneath the type wheels, and there is also provision for giving the strip a lateral feed so that the entire width of the strip can be utilized without any waste. In the construction shown, 50 a carriage is mounted to slide under the marking head and carries at one side of the head a supply reel for the marking medium and at the other side a feed roll. The carriage and roll are so actuated that the marking material is fed longitudinally after every

second impression, there being a lateral feed between each two impressions so that first one half of the strip is used and then the other half. By this sort of feed, a wider marking strip can be used and consequently 60 one of greater strength. As a further feature, the mechanism is so arranged that, where there are two lines of printing, the lateral feed of the strip can be eliminated and its full width utilized at every impression. Furthermore, since the additional 65 line of printing may be either in front of or behind the type on the type wheel, the carriage can be arranged in a suitable position for either condition without interfering with a longitudinal feed of the strip after 70 each impression.

These and other features and advantages of the invention will appear from a consideration of the following specification and 75 accompanying drawings, in which—

Figure 1 is a left-hand side elevation with some parts broken away and in section;

Fig. 2 is a front elevation with some parts removed;

Fig. 3 is a partial, right-hand elevation;

Fig. 4 is a section on the line 4—4 of Fig. 1;

Fig. 5 is a section on the line 5—5 of Fig. 2; and

Figs. 6 and 7 are details of the scraping mechanism for one of the rollers.

The work is presented on a work support 6 which underlies a type head 8 comprising a series of type wheels mounted to turn about a horizontal axis, the hubs of the wheels being provided with an opening 10 for the reception of a heating unit. The type head is carried in a vibrating arm 12 which rocks about a shaft 14 on the frame of the machine. At the sides of the vibrating arm 12 are grooves or guideways 16 arranged to support, for sliding movement, a carriage 18 which has tongues entering the 90 grooves 16. The carriage 18 carries a supply reel and the feeding mechanism for the stamping medium. As shown in Fig. 2, there extends from the right hand side of the carriage a bracket arm 20, on the end 100 of which is supported a supply reel 22, preferably held against too free rotation by a tension device. The marking medium is in the form of a strip 24 which passes from the supply reel 22 under a roller 26, then 105

below the type wheels and around the feed roller 28 between said roller 28 and a pressure roller 30. All of these rollers are made of some material which will not conduct 5 heat, such as compressed asbestos fibre, so that the portions of the strip not directly acted upon are protected from the heat of the head. Any other suitable material can be used. The pressure roller 30 is carried 10 in an arm 32, which hangs downwardly from a stud shaft 34 fixed on the carriage 18, the arm and roller being pressed towards the feed roller by a coiled spring 36 surrounding the stud shaft.

15 The feed roller 28 is supported for intermittent rotation in the following manner: A stud 40 is fixedly secured in a bracket on the carriage 18 and supports for rotation a bushing 42 having at one end a toothed member 44, keyed by means of the pin 46 to the feed roller 28. Within a hollow extension of the feed roller, there extends a second toothed member 48 fixed on the end of a slide rod 50 arranged for limited endwise movement on 20 the oscillating arm 12. The rod 50 is provided with a helical slot 52 into which extends a pin on a block 54 which slides in a guide-way 56 on the oscillating arm. The inner end of the slide rod 50 is reduced in size and 25 is provided with stop collars 58 and 60 which limit its movement by engagement with an adjusting sleeve 62 surrounding an extension 64 from the arm 12. The adjusting sleeve 62 carries a pin 66 arranged to 30 engage selectively in openings 68 and 70 of the extension, said pin being pressed upwardly into one of the openings by a spring 72 and being withdrawn by the aid of the cap piece 74. As will hereinafter appear, 35 the purpose of this adjustment is to set the slide rod in such an initial position that a feed of the strip will take place when the carriage is fixed in either its forward or rearward position for two-line marking.

40 The means for rotating the feed roller and sliding the carriage will now be described. The block 54 receives a reciprocating movement through a link 76 pivoted at one end to the block and at the other end to a slot-toed arm 78 on a hub which is rockable on the shaft 14, a thumb screw 80 being provided to adjust the pivot in the slot and thereby control the throw of the link. The hub is rocked on the shaft 14 by an arm 82 45 which may be connected in any suitable way to the drive shaft of the machine. A third arm 84 on the rockable hub has a connection through a link 86 with an arm 88 which rocks loosely on a shaft 90 extending across the vibrating arm 12. The arm 88 carries 50 a pawl 92 which is pressed by means of the spring 94 against a ratchet wheel 95 fixed on the shaft 90 and arranged to cause the intermittent rotation of a pair of cams 96 55 also fixed on the shaft at the ends thereof.

The cams 96 cause the lateral movement of the carriage and are provided, in the illustrated construction, with high parts 98 arranged 90° apart, each high part being followed by a depressed portion 100 which is 70 concentric with the shaft 90 and this portion being followed by an incline 102 extending out to the next high part of the cam. Extensions 104 of the carriage 18 carry at their ends rollers 106 riding on the peripheries 75 of the two cams, a spring 108 holding the roller against the cams and serving to retract the carriage whenever the cams are rotated to allow this action. As shown in Figs. 6 and 7 the pressure roller 30 is provided with a plurality of grooves 110 while a bar 112 extending parallel to the roller has a corresponding series of scrapers 114 extending into the grooves and constructed 80 to prevent the strip of marking medium 85 from adhering to said roller.

Assuming that the parts are arranged as shown in Fig. 1, with the carriage in its forward position, and that an impression has just been made upon the rearward half of 90 the strip, oscillation of the arm 88 during the next vibrating movement of the head causes the intermittent rotation of the cams 96 in a clockwise direction, as viewed in Fig. 1. As soon as the rollers 106 ride off of the high parts 98 of the cams, the carriage 18 is moved to its rearmost position by the spring 108. Meanwhile the block 54 is moved forwardly, first causing an endwise movement of the slide rod 50 to an extent 95 permitted by the lost motion between the sleeve 62 and the stop collar 58, this action carrying the toothed member 48 into engagement with the corresponding toothed member 44 on the feed roller 28. Thereafter, the forward movement of the block 54, by reason of its connection with the helical groove 52, imparts a rotation to the rod 50 and, therefore, to the feed roller. This action draws a fresh supply of stamping medium from the supply reel 22. The next time that the marking head descends upon the work the impression is made against the forward half of the marking strip. Upon the reverse movement of the oscillating arm 115 88, the pawl 92 rides over the ratchet 95, to secure a new grip for the subsequent operation and the block 54, in its reverse movement, first moves the slide rod 50 to disengage the clutch members and thereafter rotates the rod idly. The cam rollers 106 now lie upon the concentric portions 102 of the two cam ends, as the cams are again given their intermittent rotation, the inclines 102 120 feed the carriage forward again. This forward movement of the carriage withdraws the toothed member 44 out of engagement with its corresponding toothed member 48 so that, as the block 54 is again moved forward, the rotation of the rod 50 will cause 125 130

no rotation of the feed roller and hence no longitudinal feed of the stamping strip. In this position, the next marking operation takes place against the rear half of the strip.

- 5 It is apparent that by the above described construction the forward half of the ribbon is first impressed on the work, then there is a lateral feed so that the rear half of the ribbon can be utilized, and then there is both 10 a longitudinal feed of the ribbon and a lateral feed again to bring the forward half of the ribbon into working position.

Whenever the machine is used with the so-called stock plate to furnish a second line 15 of printing characters behind the characters on the type wheels, the lateral feed mechanism is put out of action by removing the pawl 92 from engagement with its ratchet. The cams are then fixed in a position such that the carriage 18 is retained in 20 its rearward position, thereby bringing the toothed members into approximate contact. Under these conditions, every forward movement of the block 54 causes engagement of 25 the toothed members and, therefore, a feeding movement of the strip takes place after every impression. If the stock plate with the second line of printing lies in front of the type wheels, the cams 96 are fixed in 30 such a position that the carriage is retained in its forward position as shown in Fig. 1. Then the adjusting sleeve 62 is moved forwardly until the pin 66 engages in the opening 70. In this position of the parts, the 35 two toothed members can be brought into engagement upon the forward movement of the block 54 and a feed movement takes place after every impression as before.

Although the invention has been described 40 by reference to a specific machine, it should be understood that the invention is not necessarily limited thereto.

Having thus described my invention, what I claim as new and desire to secure by 45 Letters Patent of the United States is—

1. In a marking machine having an impression member, means for intermittently feeding a strip of marking medium to the impression member, and mechanism for automatically causing a relative movement of the strip and the impression member widthwise of the strip to utilize different lateral portions of the latter.

2. In a marking machine having an impression member, means for intermittently feeding a strip of marking medium to the impression member, mechanism for automatically causing a relative movement of the strip and the impression member widthwise of the strip to utilize different lateral portions of the latter, and means for throwing said mechanism out of operation to allow the longitudinal feed of the strip without the relative lateral movement.

3. In a marking machine having an im-

pression member, means for intermittently feeding a strip of marking medium under the impression member, and means for setting the strip in selective lateral positions to cause either half of the strip to pass under 70 the impression member.

4. In a marking machine having an impression member, means for intermittently feeding a strip of marking medium to the impression member, mechanism for automatically feeding the strip widthwise to utilize the full width of the strip, means for throwing the lateral feed mechanism out of operation, and means for setting the strip in selective lateral positions to cause either 75 80 half of the strip to pass under the impression member.

5. In a marking machine having an impression member, means for feeding a strip of marking material step by step in the direction of its length to the impression member, and means for giving the strip a lateral feed movement in the direction of its width to utilize the full width of the strip for marking. 90

6. In a marking machine, an arm having a marking head, a carriage movably mounted on the arm, strip stamping medium supported on the carriage below the marking head, means for moving the carriage to 95 change the lateral position of the strip after one marking operation, and means for moving the carriage and feeding the strip longitudinally after the next marking operation.

7. In a marking machine, an arm having a marking head, a carriage mounted to slide along the arm, a supply reel for strip stamping medium mounted on the carriage at one side of the marking head, feed mechanism for the strip mounted on the other side of the head, and means for actuating the feed mechanism and sliding the carriage. 100

8. In a marking machine, a vibrating arm having a marking head, a carriage movably mounted on the arm, feed mechanism for strip stamping medium supported on the carriage, means for moving the carriage along the arm, and means for actuating the feed mechanism to feed the strip. 110

9. In a marking machine, a vibrating arm having a marking head, a carriage mounted to slide along the arm, and mechanism supported on the carriage for presenting marking medium in strip form to the marking head. 115

10. In a marking machine, a frame, an arm mounted to rock on the frame and carrying a marking head, a carriage movably mounted on the rocking arm, strip marking medium supported by the carriage, and 120 125 a cam mounted on the rocking arm and constructed and arranged to engage the carriage to move it along the arm for presenting the marking medium in the desired relation to the head. 130

11. In a marking machine, a frame, an arm mounted to rock on the frame and carrying a marking head, a carriage movably mounted on the rocking arm, strip marking medium supported by the carriage, a cam mounted on the rocking arm and constructed and arranged to engage the carriage to move it along the arm for presenting the marking medium in the desired relation to the head, and ratchet mechanism for intermittently rotating the cam.

12. In a marking machine, a frame, an arm mounted to rock on the frame and having a marking head, a carriage movably mounted on the rocking arm, a feed roller for strip marking medium supported on the carriage, and means for intermittently rotating the roller to feed the strip.

13. In a marking machine, an arm having a marking head, a carriage movably mounted on the arm, a feed roller for strip marking medium supported on the carriage, a clutch member secured to the feed roller, a rod having a clutch member, and means for effecting engagement of the clutch members and for rotating the rod to cause the roller to feed the strip.

14. In a marking machine, a marking head, and means for presenting strip marking medium to the head, said mechanism comprising a feed roller having a clutch member, a rod having a co-operating clutch member, and means for sliding and rotating

the rod to effect intermittent rotation of the feed roller.

15. In a marking machine, a marking head, and means for presenting strip marking medium to the head, said mechanism comprising a feed roller, a rod engageable with the roller and having a helical groove, a member engaging the groove and held against rotation, and means for reciprocating the member to rotate the rod and cause feeding movement of the strip.

16. In a marking machine, a marking head, and means for presenting strip marking medium to the head, said mechanism comprising a feed roller, a rod having a curved groove and provision for limited longitudinal movement, co-operating clutch members on the rod and the feed roller, a sliding block engaging the curved groove, and means for sliding the block to engage the clutch members and rotate the feed roller.

17. In a marking machine having a movable marking head with provision for heating said head, and mechanism mounted to move with the head for leading a marking medium in strip form under the head, said mechanism comprising rollers of non-conducting material at the sides of the head to protect the strip from the heat.

In testimony whereof I have signed my name to this specification.

DENYS WARWICK MORLEY.
